(57) CLAIM

The ornamental design for a watch strap, as shown and described.

DESCRIPTIONFIG. 1 is a front and right perspective view of a watch strap in its use state, showing my new design;
FIG. 2 is a rear and right perspective view thereof in its use state;

FIG. 3 is a front, left and top perspective view of a watch strap showing my new design;

FIG. 4 is a front view thereof;

FIG. 5 is a rear view thereof;

FIG. 6 is a right side view thereof;

FIG. 7 is a left side view thereof;

FIG. 8 is a top plan view thereof; and,

FIG. 9 is a bottom plan view thereof.

The broken lines in FIGS. 1 and 2 depict environmental subject matter and form no part of the claimed design.

1 Claim, 9 Drawing Sheets(56)
